UNITED STATES PATENT OFFICE.

NELSON H. SMITH, OF SPRING VALLEY, ILLINOIS.

COLLAPSIBLE STOVE.

Application filed January 30, 1923. Serial No. 615,869.

To all whom it may concern:

Be it known that I, NELSON H. SMITH, a citizen of the United States, and resident of Spring Valley, in the county of Bureau 5 and State of Illinois, have invented certain new and useful Improvements in Collapsible Stoves, of which the following is a specification.

This invention relates to collapsible stoves 10 especially adapted for use in camping through not necessarily restricted to such use.

Briefly stated an important object of this invention is to provide a knock-down stove 15 which may be compactly folded so that the same will occupy but a small amount of space when being transported from place to place.

A further object is to provide a knock- 20 down stove which may be conveniently and quickly set up and wherein the supporting legs constitute a means to hold the sides of the stove in position and to prevent the collapse of the stove.

25 A further object is to provide a collapsible stove having a novel form of chimney or pipe which may also be collapsed for transportation purposes.

30 A further object is to provide a stove of the character specified which is of highly simplified construction, durable in use and cheap to manufacture.

35 Other objects and advantages will be apparent during the course of the following description.

In the accompanying drawing forming a part of this application and in which like numerals are employed to designate like parts throughout the same,

40 Figure 1 is a group perspective of a stove constructed in accordance with this invention,

45 Figure 2 is a vertical sectional view through the same, the stove pipe being shown partly in section.

Figure 3 is a bottom plan view of the stove collapsed,

Figure 4 is an edge elevation of the stove folded.

50 Figure 5 is a horizontal sectional view through the stove pipe.

In the drawing wherein for the purpose of illustration is shown a preferred embodiment of the invention the numeral 5 gener-

ally designates a top formed from sheet iron 55 or other suitable material and having a continuous depending flange 6 which not only constitutes a reinforcing means for the stove but also forms a convenient means whereby hinges 7 may be secured to the top. It 60 will be seen that the side walls 8 are hingedly secured to the flanges 6 through the medium of the hinges 7 and when the stove is in its operative position as illustrated in Figure 1 a plurality of legs which 65 are pivotally connected to the flanges 6 as indicated at 11 are driven into the ground and prevent inward swinging movement of the sides 8. That is to say the legs 10 which are arranged in pairs at opposite sides of 70 the top 5 engage the side walls 8 and thereby hold the top in an elevated position and also prevent the uncontrolled swinging movement of the sides 8.

End walls 15 are hingedly connected to 75 the continuous flange 6 as indicated at 17 and the beaded lower edges 16 may engage the end walls 15 and thereby prevent the end walls from swinging inwardly and permitting the stove to collapse when in use. 80

In carrying out the invention the end wall at one end of the stove may be provided with a fire door 20 by means of which the fire may be supplied with wood or other fuel. A suitable draft plate 22 may be rotatably connected to the fire door and adjusted as the occasion requires. 85

Figures 1 and 2 illustrate that the top wall 5 may be provided with an opening 80 which is surrounded by a continuous flange 90 31 to which a stove pipe generally designated by the numeral 33 is detachably connected.

With reference to Figure 5 it will be seen that the stove pipe 33 is composed of side 95 and end walls 34 and 36 respectively, the vertical edges of which are formed with interlocking flanges 37. The pipe too may be knocked down when desired by simply separating the side and end walls by sliding 100 the interlocking flanges out of engagement with each other.

In carrying out the invention the side and end walls may be provided with diagonal intersecting ribs 50 as illustrated and the 105 stove may be otherwise reinforced.

With reference to the foregoing description taken in connection with the accom-

panying drawings, it will be seen that when it is desired to collapse the stove legs 10 are merely withdrawn from the ground and swung into parallel relation with the depending flanges 6 and the side walls 8 are subsequently swung inwardly into overlapping relation as illustrated in Figure 3.

The device in use provides a convenient stove and one in which an extremely hot fire may be made. The top 5 of course serves as a supporting means for various cooking utensils and the like and when it is desired to supply the fire with additional fuel the door 20 may be opened. A suitable latch 70 may be employed for holding the door closed.

Having thus described the invention, what is claimed is:—

A collapsible stove comprising a top having its side and end portions bent to define integral side and end reinforcing flanges, side and end walls hingedly connected to said flanges and adapted to be swung directly beneath said top, supporting legs pivotally connected to the inner sides of said side flanges adjacent the ends thereof and terminating below said sides, said legs being located inwardly of said sides to limit the inward swinging movement of the same, and a fire door carried by one of said ends. 20 25

NELSON H. SMITH.
